UNITED STATES PATENT OFFICE.

OLIVE W. DENNIS, OF BALTIMORE, MARYLAND.

VENTILATOR.

Application filed December 13, 1927. Serial No. 239,777.

While my improved ventilator may be used in various places, it is primarily designed to be used in connection with railroad cars.

5 Pullman cars, chair and sleeper and dining cars are equipped with screens for the purpose of keeping out cinders and the like, and to some extent they function as ventilators but they, as it is well known, do not protect the passengers from drafts, and many passengers prefer to have the windows closed rather than sit in a draft.

10 Day coaches are not provided with screens or any type of ventilator in present railroad practice.

15 It is not practical to provide cars with ventilators and screens which can be readily removed by the passenger because they would become lost and damaged, besides which it is practically impossible to prevent drafts through the joints around the perimeter of the ventilator. It is objectionable to build a ventilator into the window sash because it frequently interferes with the passenger's 20 vision, besides which it interferes with the ready raising and lowering of the sash, the ventilator adding weight to the sash. Ventilators for cars which are placed between the bottom of the sash and the window sill 25 must be removed when the window is raised, and this is objectionable because of the liability of loss and damage to the ventilator, to say nothing of the scarring of the car in the insertion and removal of the ventilator.

30 The object of my invention is to provide a ventilator for all types of cars, free from the known objections of ventilators now in use.

35 Another object of my invention is to provide a ventilator which is rigidly attached to, or built into the car body thereby eliminating all possibility of leaky joints, and the entrance of cinders, etc.

40 Another object of my invention is to provide a ventilator without cumberon attachments to the window frame or sash to interfere with the passenger's view through the window.

45 Another object of my invention is to provide a car ventilator which can be used with double sash windows without requiring the opening of the inner sash.

50 Another object of my invention is to provide a ventilator for cars which can be readily cleaned without detaching it from the car, and without tampering with the parts

of the ventilator visible from the inside of the car, thereby eliminating the liability of marring the original smooth finish of the car interior.

60

Another object of my invention is to provide a ventilator for cars which is entirely under the control of the passenger, and which can be operated with a very slight physical exertion; and with these and other objects 65 in view, my invention consists of the parts and combination of parts as will be herein-after pointed out.

65

In the drawings:

Figure 1 is a front elevation of my improved ventilator.

Figure 2 is a rear view of Figure 1.

Figure 3 is a top plan view of Figure 1, parts being in section.

Figure 4 is a vertical transverse sectional 75 view through my ventilator and associated parts.

While I have illustrated my invention in connection with the standard steel car, it will, of course, be understood that it can 80 be used with equal efficiency with any other type of car.

85 The reference numeral 1 designates the outer face plate of the car wall, the inner face plate being designated by the numeral 2. In this outer face plate there is a housing 3 having top, bottom and end walls, said housing having flanges 4, 5, 6 and 7, the flange 6 being provided with screw holes 8. At the top the housing has a depending flange 8 90 spaced in front of the flange 7 thereby forming a groove 9 between said flanges 7 and 8. A detachable screen frame 10 is secured in the housing by sliding its upper edge into the groove 9 and fastening it in that position 95 by means of the screws 11. This frame is of the grid type and its inner face is covered with a very fine mesh wire cloth 12 secured thereto in any suitable manner. This screen 12 closes the ventilator against cinders 100 and the like, but permits air to freely enter the housing. By simply removing the screws 11 the screen can be removed for cleaning, and at the same time permit of cleaning of the interior of the housing.

105

100 A pull plate or lid 13 is secured to and flush with the inner face plate of the housing or the car wall by means of a hinge 14, and is provided with a countersunk pull 15, said plate or lid being provided at each end with an inwardly extending flange or wings 16, each having an arcuate shaped top edge provided

110

with an inwardly extending flange 17 to which flanges I secure in any desired manner a perforated flat plate 18 formed on an arc complementary with the arc of the top edges of the plates 16. This perforated plate 18 is provided at its outer edge with an upstanding flange 19 to be hereinafter referred to.

Within the housing I secure a grooved strip 20, which is located on the end walls 10 and the top wall of the housing, and positioned back from the plane of the inner face of the inner car wall plate 2. The end and top edge portions of the pull plate or lid 13 are inturned to form a flange 21 which is 15 adapted to enter the groove of the strip 21, thereby forming an interlocked joint between the car wall plate 2 and the pull plate. To further seal this joint, I preferably pack it 20 with a suitable material 22, such as sponge rubber. This packing not only serves to seal the joint, but also functions as a cushion to deaden, if not eliminate, the noise incident to the closing of the ventilator lid; without a packing metal would contact metal.

25 From the above it will be seen that the pull plate or lid 13 and its flanges 16 constitute a frame adapted to swing on its hinge 14, which frame carries the perforated plate 18 which constitutes the top of the frame.

30 A plate 23 is secured to the bottom wall 6 of the housing and is provided with spaced lugs 24 connected by a pin 25 on which are journalled two arms 26 between the outer ends of which a roller 27 is journalled. These 35 arms are connected intermediate their ends by a bridge 28. A spring 29 is coiled around the pin 25 with one end anchored on the plate 23, while its one end is anchored on the bridge 28 of the arms 26, whereby the tendency of the 40 spring is to swing the arms toward the pull plate 13. On the inner face of the pull plate 13 I secure a plate 28 which is provided with an integral forwardly extending cam like 45 protuberance 28^a, which is adapted to engage the roller 27 and cooperate therewith to hold the ventilator frame firmly in open or closed position, as will be readily understood from the drawings.

To open the ventilator it is only necessary 50 to swing the frame inward of the car whereupon air is free to pass through the screen into the housing and thence into the car through the perforated plate. The lid and the flanges

16 throw the currents of air upward, avoiding any direct strong drafts upon the arm or body of the passenger occupying the seat adjacent the ventilator, and entirely eliminating strong drafts on the occupant of the seat behind.

There are no projecting parts in the car 60 of the ventilator when closed and even when it is open it occupies so little space that it does not interfere with the passenger's comfort in resting his arm on the window sill.

There is no difficulty whatever in having 65 windows either open or shut with my ventilator, and the ventilator works as efficiently in summer as in winter. If a storm necessitates the closing of the car windows, ventilation can 70 still be obtained through my improved ventilator which will not admit the entrance of rain.

The perforated plate 13 prevents persons 75 from cramming trash into the ventilator and interfering with the efficiency of the ventilator.

What I claim is:

1. In a car ventilator, the combination with a housing having top, bottom and end walls, of a movable lid adapted to close one side of the housing, a screen to close the other side of the housing, wings extending inwardly from the ends of the lid and constituting with the lid a chute to direct air currents upwardly, a perforated cover overlying the lid and wings, 80 a cam on the inner side of the lid, an arm in the housing coacting with said cam to lock the lid in both open and closed positions, and means holding said arm constantly in co-operative relation with said cam.

2. In a ventilator for cars, the combination with a housing having top, bottom and end walls, a screen closing one side of the housing, and a hinged lid closing the other side of the housing, wings extending inwardly from the ends of said lid, a perforated plate mounted on the top of said wings, a stop on said plate to limit the outward movement of the lid, a cam carried by said lid, a spring controlled arm pivotally mounted within the housing, 95 and a roller carried by said arms and in constant engagement with said cam to lock the lid in an adjusted position.

In testimony whereof I affix my signature.

OLIVE W. DENNIS.
